CLAIM

I claim ornamental design for the table, as shown and described.

DESCRIPTION

FIG. 1 is a top and front perspective view of the table; FIG. 2 is a bottom and side perspective view of the table; FIG. 3 is a side perspective view of the table with the front leg partially collapsed, alternative position, and with the left side being a mirror image thereof; FIG. 4 is a bottom perspective view of the table; FIG. 5 is a bottom perspective view of the table in a fully collapsed, alternative position; and, FIG. 6 is a rear end view of the table.
